ATTORNEY.

UNITED STATES PATENT OFFICE.

JOHN D. HARRELL, OF BELLEVIEW, FLORIDA.

HASP.

1,377,344.

Specification of Letters Patent. Patented May 10, 1921.

Application filed October 26, 1920. Serial No. 419,747.

To all whom it may concern:

Be it known that I, JOHN D. HARRELL, a citizen of the United States, residing at Bellevue, in the county of Marion and State of Florida, have invented certain new and useful Improvements in Hasps; and I do hereby declare the following to be a full, clear, and exact description of the invention, such as will enable others skilled in the art to which it appertains to make and use the same.

This invention relates to improvements in hasps and more particularly to such as are adjustable, the object of the invention being to provide a simple and efficient hasp construction which can be readily adjusted to the position of the staple with which it may be connected, although the latter may, on account of sagging of the door or gate or the settling of a door jamb or post, be out of position to permit the hasp readily to be applied thereto.

With this and other objects in view, the invention consists in certain novel features of construction and combinations of parts as hereinafter set forth and pointed out in the claims.

In the accompanying drawings, Figure 1 is a view showing an embodiment of my invention; Figs. 2 and 3 are views showing different positions of adjustment of the parts; Fig. 4 is a longitudinal sectional view, and Fig. 5 is a transverse section.

My improved hasp comprises two flat metal bars 1 and 2, the latter being provided near one end with a hole to receive a staple or other fastening means whereby the device may be attached to a door or gate. The bar member 2 overlies a portion of the bar member 1 and the latter is pivotally connected near its rear end to an intermediate portion of the former as indicated at 3. The member 2 is provided near its forward end with a transverse slot 4 which receives a headed pin 5 projecting from an intermediate portion of the member 1 to permit limited vertical movement or adjustment of the latter.

The bar member 1 is made with an elongated slot 6 to receive a staple 7 projecting from a door frame or gate post, and the bar member 2 is provided with an elongated slot 8 to permit longitudinally movable pivotal connection of a hook bar 9 therewith, through the medium of a pin 10 carried by said hook bar and movable in said slot 8. The hook bar 9 extends over the forward

end of the bar member 2 and partially over the bar member 1, so that the hook 11 of said bar 9 may be made to engage the staple 7.

With the use of my improvements, the hook bar 9 may be moved longitudinally so that its hook will be permitted to easily and properly engage the staple and thus avoid the necessity of accurately locating the point of fastening of the hasp to the door or gate or the position of the staple on the door frame or gate post. By reason of the pivotal connection between the two bar members, the member 1 may be raised or lowered to cause its slotted portion to properly engage the staple on the door frame or gate post if said staple be not in proper position by reason of shrinkage or settling of the part to which it may be secured, or from other cause.

My improvements are simple in construction and provide a hasp which may be easily manipulated to readily engage a staple under any conditions which may be encountered.

Having fully described my invention what I claim as new and desire to secure by Letters-Patent, is:—

1. A hasp comprising two members connected by a horizontal pivot to permit of angular movement of the members with relation to each other, means for limiting such angular movement, one of said members adapted to be pivotally connected adjacent its free end with a gate or gate post and the other member provided with a slot to receive a staple secured to the gate post or gate, and a hook bar having longitudinally movable and pivotal connection with the pivotal member of said hasp and adapted to engage the staple passing through the slot in the other member of the hasp.

2. A hasp comprising two members, one overlying the other and pivotally connected together, such pivotal connection being located near one end of one of said members and intermediate of the ends of the other member, one of said members having a transverse slot and the other member having a pin entering said slot, one of said members having a staple slot and the other member having an elongated slot, and a hook bar provided with a pin movable in said last-mentioned slot and pivotally connecting said hook bar with the member having said slot.

3. A hasp composed of two members one

of which is transversely pivoted adjacent one end to the other member intermediate the ends of the latter, means connecting the two members for limiting the pivotal movements of said members with relation to each other, one of said members having a hole at its outer end for permanent attachment to a support and the other member having a slot adjacent its outer end to receive a staple and a hook bar carried by the hasp member adapted for permanent attachment to a

support, and adapted to engage the staple passed through the slot in the other member of the hasp.

In testimony whereof, I have signed this 15 specification in the presence of two subscribing witnesses.

JOHN D. HARRELL.
